RADIOANTENNA

Victor F. Emerson, Philadelphia, Pa., and William L. Edison, Wilmington, Del.

Application December 8, 1931. Serial No. 579,794

8 Claims. (Cl. 179—2.5)

The invention to which the following description relates is an improvement in the system or circuit assembly of radio antennæ. It is customary to supply the radio impulses to a broadcast receiver by means of a system of wires which must have a predetermined characteristic suitable for the wave lengths desired. This necessitates an antenna of considerable length and so disposed as to collect the maximum radiant energy. The consequence of this is that in many instances the broadcast receiver is dependent upon an antenna system which must be extended outside of the building housing the receiver. In this way the antenna system is objectionable because of its conspicuousness and unsightliness. It also follows that the antenna delivers to the receiver not only the desired impulses but many extraneous ones which cause audible disturbances and in many instances irregular operation of the receiver.

It is also characteristic of radio receivers that their manual operation permits their being controlled only by an operator at the receiver itself and this is many times awkward when those listening are within the sound of the receiver but not close enough to operate it by hand.

It is an object of our invention to provide for the ordinary broadcast receiver of radio signals, a system by which the signals of radio frequency may be collected and delivered to the receiver without the use of an outside antenna and its consequent fire hazards, unsightliness and expense.

It is a further object of our invention to utilize the existing common telephone lines and the prevailing types of telephone instruments for collecting the desired radio impulses.

In the development of our invention it will also be apparent that the devices may be incorporated in a standard telephone instrument and thus become an auxiliary to the telephone service.

A conspicuous advantage in this improved device is the facility which it affords for the control of the operation of the broadcast receiver by the person using the telephone instrument. There are many times when the one listening to the radio receiver desires to use the telephone but finds that the operation of the radio receiver is a distraction or annoyance. Under such circumstances the use of the device puts the operation of the radio receiver under the sole control of the listener who is using the telephone instrument even though this instrument is remote from the radio receiver.

As illustrating the invention in its essential features and without undue limitation to the invention, we have illustrated the preferred form of the invention in the following drawing in which:

Fig. 1 is a side sectional elevation of the device;

Fig. 2 is a similar view of the device as incorporated in the standard of the conventional telephone instrument;

Fig. 3 is a horizontal section looking upwardly on the line 3, 3 of Fig. 1 and

Fig. 4 is a diagrammatic view of the electrical circuit involved.

The preferred form which the invention may take and as illustrated in the above mentioned drawing, consists essentially in a base which carries a spiral coil forming the collector of radio impulses. This coil may have its effect intensified by the presence of a metallic plate which may form one part of an air condenser. In Fig. 1 we have shown the housing 6 to consist of a molded plastic substance the upper edge 7 of which overlies the metallic disc 8.

Beneath the metallic disc 8 is a spiral coil 9 formed of insulated wire. One end 10 at the center of the coil 9 is soldered to the center of the disc 8 while the opposite end 11 of the coil is connected to the toggle switch 12.

The toggle switch 12 has a lever 13 which is intended to project beyond the side wall of the base 6.

A lead 14 from the toggle switch 12 connects the latter with a variable resistance or condenser 15 as shown in Fig. 1. An operating knob 16 extends from the resistance or condenser 15 outwardly of the base 6. A second conductor 17 runs from the opposite contact of the switch by way of the movable element of the resistance or condenser 15 out of the base through the opening 18. This conductor 17 is intended to be attached to the ground connection G of the usual radio broadcast receiver 19.

Suitable means of supporting the coil 9 in proximity of the plate 8 may be provided in any desired manner. This may take the place of windings of adhesive tape, transverse supporting struts, or as we have illustrated in Fig. 1 the coil 9 may be held in position by means of cement or plastic 20. When this form of assembly is followed the plate 8, coil 9, switch 12 and volume control 15 are all cast in place in the operation of molding the base 6.

A second conductor 23 attached to the opposite side of switch 12 passes out of opening 18 and

is attached to the antenna connection A of the broadcast receiver.

The device as above illustrated is proportioned to form a foundation for the ordinary telephone receiving instrument indicated broadly as 24. Such an instrument has a base 25 with a felt or fabric covering 26 which rests upon the plate 8 as shown in Fig. 1. Since the telephone instrument 24 is electrically connected to the telephone line it serves as one plate of an air condenser of which the other plate is the disc 8. This condenser serves to intensify and strengthen whatever radio energy may be gathered by the telephone line. In this way the plate 8 and the associated parts may be said to be within the direct influence of the radio waves or within the zone of radiant energy.

While the above description applies to the invention as it may be separately constructed, it is equally true that the invention may form a direct part of the telephone instrument and thus a desired auxiliary to the telephone service. In Fig. 2 we have illustrated the construction of the invention when so arranged. In this modification the shell 24 of the telephone fits a metallic base 27 which has a felt or fabric covering 26. The base 27 is bolted at three points 28 to the telephone standard or the shell 24 in well known manner.

30 The coil 9 in this instance is laid upon the bottom 27 and has its center point 10 connected to one of the bolts 29 by which the base 27 is attached to the telephone standard.

35 The outer end of the coil 9 is attached to the switch 12 in the manner already described. The volume control device 15 is connected to the switch and to the ground connection of the broadcast receiver in the manner described. It is evident that both the switch 12 and the volume control 15 may form integral parts of the shell 24 or be mounted therein in any suitable way so long as it is possible for the switch lever 13 and the volume control member 16 to be operated from outside of the driven standard.

40 45 The conductor 23 extending from the switch to the ground connection of the broadcast receiver is also arranged as previously described.

In Fig. 4 there has been shown the electric circuits upon which the invention relies. The base 24 of the telephone is shown to co-operate with the plate 8 as an air condenser. The coil 9 of suitable electrical characteristics is connected primarily to the antenna connection A by-passing the volume control 15. During normal operation of the broadcast receiver 19 this assembly supplies the collecting system ordinarily found in antennæ but with the advantage of compactness and freedom from undesired electrical disturbances.

60 65 The switch 12 serves to connect the collecting system to ground through the conductor 17 and the connection G on the broadcast receiver. Indirectly this serves also to ground the antenna connection A of the receiver. It follows that on operation of the switch lever 13 the broadcast receiver is put out of operation, for so long as the switch 12 is in closed circuit with the conductor 17.

In the modification shown in Fig. 2 the capacity effect is supplied between the part of the telephone instrument in contact with the connection 10 and other parts of the telephone line.

70 75 With the device assembled as a separate article as shown in Fig. 1 it is put in operation through use as a rest for the telephone trans-

mitter standard and connecting the wires 17 and 23 to the broadcast receiver. Used as an auxiliary to the telephone service the device is assembled within the transmitter standard as shown in Fig. 2 and the lead wires 17 and 23 form part of the usual telephone cable, being likewise connected to the broadcast receiver.

The one desiring to listen to the radio, operates it in the usual manner and will find that the antenna system has marked advantages in sharpness of tuning, clarity of tone and freedom from electrical disturbances.

If it is desired to use the telephone, which may be at a considerable distance from the broadcast receiver and connected thereto by long leads 17 and 23, then the listener need not go to the broadcast receiver to put it out of operation but when using the telephone need only vary the volume control to prevent his own distraction or at the most by means of switch 12 he may temporarily ground the antenna connection A of the receiver for the short period during which the telephone is being used. At the conclusion of operation of the telephone, the switch 12 is thrown to open position and the radio energy is collected in the coil 9 and again delivered undiminished to the radio receiver and thus the operation of the latter restored to normal.

The above forms of the invention have been described for purposes of illustration only and not by way of limitation of the invention other than may be imposed by the appended claims.

What we claim is:

1. In combination, a metallic plate adapted to support the standard of a telephone instrument, a coil having one end attached to the plate, a switch attached to the other end of the coil, a permanent connection between the switch and the input of a radio receiver, and a switch contact to ground.

2. In combination, a metallic plate adapted to support the standard of a telephone instrument, an inductive coil having one end attached to the plate, a switch attached to the other end of the coil, a permanent connection between the switch and the input of a radio receiver, a variable resistance forming a volume control in said connection, a ground and a switch contact thereto.

3. In combination, a telephone instrument having a line connection, a radio receptive coil in capacity relation to said line connection, a conductor from said coil to the input of a radio receiver, a variable resistance forming a volume control for said conductor, a ground and a switch located in proximity to the telephone instrument and coil for grounding the coil and the input of the receiver.

4. In combination, a base, a metal plate associated therewith, an inductive coil connected to the plate, a conductor normally connecting the coil to the input of a radio receiver, a ground and a switch in the base for connecting the conductor to the ground.

5. In combination, a metal plate, a coil connected to the plate, a conductor from the coil to the input of a radio receiver, a ground, a switch for connecting the conductor to the ground and a base of suitable molded insulating material for holding the plate, coil and switch in operative relationship.

6. In combination, a telephone having a line connection, a radio receptive coil within the base of the telephone, connections from the coil to the input of a radio receiver, and a switch

on the base of the telephone for grounding said connections.

7. In combination, a telephone having a line connection, a radio receptive coil within the base 5 of the telephone, connections from the coil to the input of a radio receiver, means in the base of the telephone for manually modifying the volume of the radio impulses through said connections, and other means in the base of the 10 telephone for manually grounding the said connections.

8. In combination, an electrically conducting plate, a coil of insulating wire in juxtaposition

with one side of said plate and having one end in contact with said plate, a resistance having one end thereof connected to the other end of said wire, an output conductor attached to the same end of said resistance, a switch on the wire 80 between the coil and the resistance, a common ground conductor adapted to be connected to the resistance and to the switch and a base of plastic insulating material in which the plate, the switch and the resistance are held in fixed 85 relation.
